Inventor

Elizabeth Eunice Merrill

UNITED STATES PATENT OFFICE.

ELIZABETH EUNICE MERRILL, OF LOS ANGELES, CALIFORNIA.

DESIGN FOR A HAWAIIAN DOLL.

50,330.

Specification for Design.

Patented Feb. 13, 1917.

Application filed December 18, 1916. Serial No. 137,728. Term of patent 7 years.

To all whom it may concern:

Be it known that I, ELIZABETH EUNICE MERRILL, a citizen of the United States, residing at Los Angeles, in the county of Los Angeles and State of California, have invented a new, original, and ornamental Design for Hawaiian Dolls, of which the following is a specification, reference being had to the accompanying drawing, forming part thereof.

In said drawing:

Fig. 2, is a side elevation thereof.

Fig. 3, is a rear elevation thereof.

I claim:

The ornamental design for a Hawaiian doll as shown.
